UNITED STATES PATENT OFFICE

THOMAS H. WIGHTMAN, OF PROVIDENCE, RHODE ISLAND, ASSIGNOR TO ALFRED VESTER SONS, INC., OF PROVIDENCE, RHODE ISLAND, A CORPORATION OF RHODE ISLAND

DESIGN FOR A BUCKLE OR SIMILAR ARTICLE

Application filed August 22, 1929. Serial No. 32,505. Term of patent 3½ years.

To all whom it may concern:

Be it known that I, THOMAS H. WIGHTMAN, a citizen of the United States of America, residing at Providence, county of Providence, State of Rhode Island, have invented a new, original, and ornamental Design for a Buckle or Similar Article, of which the following is a specification, reference being had to the accompanying drawing, forming a part thereof.

Fig. 1 is a top plan view, and Fig. 2 is an edge elevation of a buckle or similar article, showing my new design.

I claim:

The ornamental design for a buckle or similar article, substantially as shown.

THOMAS H. WIGHTMAN.
